RAILWAY CAR

Charles De Los Rice, Hartford, Conn.

Application February 17, 1932, Serial No. 593,441

9 Claims. (Cl. 105—131)

This invention relates to railway cars, and has particular reference to certain improvements in driving mechanism and trucks for such cars.

It has been the practice to locate the power mechanism, such as the electric motor, on the sprung load, and to impart the power to the driven wheels through a gear mechanism rigidly mounted on the axle of those wheels. Such an arrangement is open to numerous objections, among which may be mentioned that perfect harmony between the gears cannot be maintained no matter how well the gears may be made, and the drive mechanism is subjected to excessive shocks and strains. It has been proposed to provide between the mechanism and the driven car wheels cushioning devices in order to relieve the driving mechanism of the shocks and jars which would otherwise be transmitted to it through the wheels as they pass over the rails.

The aim of my invention is to provide an improved arrangement wherein pneumatic cushions are interposed between the drive mechanism and the driven car wheels, the arrangement being characterized by its simplicity in construction, by the ease and facility with which the parts may be assembled and dis-assembled, and the security with which the pneumatic cushions are held in place on their holders and in gripping relation to the driven car wheels.

A further aim of the invention is to provide certain improvements in the construction and design of the trucks to give better riding qualities and more steadiness to the car while in motion, that will provide greater durability and dependability; permit of maintaining the necessary parts in lubricated and protected condition; which make for simplicity in construction and assembling, and which generally increase the safety factor. My improved truck is particularly characterized by its lightness in weight as compared to trucks as now used on passenger cars.

In the accompanying drawings, I have shown the improvements of the present invention applied to a car of special form, and the power plant is diagrammatically illustrated as being in the form of a gasoline motor. It is understood that this disclosure is by way of exemplification only, it being observed that my improvements may be applied to railroad cars other than of the type shown, and the motor may be of any desired nature, such, for example, as an electric motor or an engine of the Diesel type. An

electric motor may be placed beneath the car platform and adjacent the rear truck.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims. 5

In the accompanying drawings, wherein is shown, for illustrative purposes, one embodiment which the present invention may take,

Fig. 1 is a side elevational view showing, more or less diagrammatically, a car to which the improvements of the present invention may be applied; 15

Fig. 2 is a top plan view of the car shown in Fig. 1;

Fig. 3 is a side elevational view of the rear truck; 20

Fig. 4 is a top plan view of what is shown in Fig. 3;

Fig. 5 is a vertical transverse section taken centrally through the truck substantially on line 5—5 of Fig. 4; 25

Fig. 6 is a horizontal sectional view through the drive gear mechanism associated with the front axle of the rear truck;

Fig. 7 is a sectional view showing one of the car wheels and its relation to the hollow driven shaft or quill and the axle extending through that shaft; 30

Fig. 8 is an elevational view of one of the holders for the pneumatic cushions, the hollow shaft or quill being shown in end elevation and the cushion and car wheel being shown in broken lines; 35

Fig. 9 is a top plan view of the torque rod for preventing rotation of the casing within which the drive gear mechanism is located; 40

Fig. 10 is a side view of that torque rod and an end view of the casing;

Fig. 11 is an end view of the springs which are located between the platform of the car and one of the side beams of the truck, this view being taken substantially on line 11—11 of Fig. 3; and 45

Fig. 12 is an elevational view of one of the links by means of which the truck frame is suspended, this view being taken substantially on line 12—12 of Fig. 3. 50

Referring to the drawings in detail, in Figs. 1 and 2 is disclosed, for illustrative purposes only, 55

a special car to which the improvements of the present invention may be applied to advantage. In this instance, the car body is mounted upon a front truck and a rear truck, the latter having a pair of front wheels 10 which are driven, as hereinafter described more in detail. In this instance, the power unit, designated generally by the numeral 11, is located within the platform at the forward end of the car body. It may be stated here that the term "platform" means the chassis, and includes the longitudinally extending I-beams 9 which may be four in number, and the floor carried by the I-beams. The power unit may be of any suitable kind, such as an electric motor, gasoline motor, or a Diesel engine. This motor is connected to the gearing for the wheels 10 by a drive shaft, which is preferably in sections, designated by the numerals 12, 13 and 14. The latter section constitutes the driving gear shaft and is disclosed most clearly in Fig. 6. Between the sections of the drive shaft are suitable universal joints 15. It will be observed that the engine is slightly inclined so that its shaft, together with the drive shaft, is radially disposed with respect to the axis about which the wheels 10 rotate, so that there is a minimum of cramping action and wear on the universal joints. There may be a universal joint 15' immediately behind the motor as a protection to its crankshaft. The front wall of the car body slopes upwardly and rearwardly, as at 18, so as to reduce wind resistance as much as possible. The front end of the car may have a gable 19 provided with a window through which the operator may observe the road bed. The engine compartment at the forward end of the car may be separated from the passenger compartment by a transverse partition 20. In order to reduce suction at the rear end of the car, there may be secured to the car body a horizontally disposed pyramidal member 21 which has here been more or less diagrammatically illustrated. The car is given generally streamline shape, without introducing weaknesses therein or sacrificing space or comfort. The pyramidal member may be removable so as to permit of a number of cars being made up into a train; where this is the case, the member 21 is connected to the rearmost car. It may be here observed that the car body sets relatively low on the trucks so that the center of gravity of the car is brought nearer the rail line, which is of distinct advantage, from the safety standpoint. Also, this makes it easier to get into and out of the car. As pointed out hereinafter more in detail, the truck springs are spaced a maximum distance apart, so that side rolling is greatly reduced.

Reference will now be had to the manner in which the drive mechanism for the driven car wheels is supported by pneumatic cushions in order that the transmission of shocks and jars from the wheels to the drive unit is reduced to a minimum. The rear truck has a pair of longitudinally extending bolsters or beams 25 which are preferably in the form of an H, and these beams are connected together by transverse I-beams 26, and a top plate 27, the latter being riveted to the upper flanges of the beams 25. The I-beams may be connected to the H-beams 25 by means of plates 28, as shown most clearly in Fig. 5. Thus the beams are so secured together that they are held against changing their relative positions in a horizontal plane, there being sufficient flexure vertically relative to the spring 75 of each bearing to allow all four wheels to equally

support the load at all times. The forward ends of the H-beams 25 are suspended, as hereinafter described more in detail, from journal boxes, designated generally by the numeral 24 and carried by the opposite ends of a solid axle 29 which fixedly carries the driven wheels 10 (see Fig. 7). About the axle 29 is a hollow tubular shaft or quill 30 which carries the drive unit, and this shaft is supported in a cushioned manner by the wheels 10, there being sufficient clearance between the axle 29 and the shaft to prevent contact therebetween. Secured to each end of the hollow shaft 30 is a holder for a pneumatic cushion which seats in a tight non-slipping manner upon an internal circumferential surface provided on the 15 car wheel.

In the present instance, the cushion has a ringlike casing 31, preferably formed of rubber and fabric, or cord as commonly applied in tire practice. The casing is provided with wired beads 32 on its inner circumference. The casing may be moulded so that it has an elliptical form so that the strains are distributed evenly on the cords of the cushion, greatly adding to the life and durability thereof. Within the casing 31 is an inner tube 33 to which leads a valve 34. The car wheel is provided with an annular container or flange 35, the internal surface 36 of which is parti-elliptical, transversely. The pneumatic cushion, when inflated and if not confined 30 against outward expansion, would normally take a form cylindrical in cross section, but as this cushion is held between its holder and the container 35 and the container measures less than the normal diameter of the cushion when inflated, the cushion will flatten out and take a somewhat elliptical shape, thus affording a broad bearing surface between the container 35 and the cushion, thereby effecting a completely dependable driving engagement between the members 40 when the cushion is inflated at a moderate pressure comparable with auto tire practice; and also permitting, at the same time, the desired pressure necessary to a proper cushioning of the driving mechanisms.

The holder for the cushion is of improved and novel construction, the arrangement thereof being such that its parts may be readily manufactured and assembled and the cushion, when the parts are assembled, is very securely and 50 safely held against movement relative to the holder. The holder has a body portion 37 and a clamping plate 38 secured to the body member by bolts 39 of suitable number, say twenty. The body member and the clamping plate have 55 flanges 40 the outer surfaces of which are suitably inclined so as to form a seat for the inner periphery of the casing 31. Also, these members are recessed at the base of the seat in order to conform to and closely receive the beads 32, as shown in Fig. 7 of the drawings. The holder also includes an intermediate ringlike disc, preferably formed of three arcuate sections or plates 41 of such length that when these parts are assembled end to end there is a space 42 between two of the 65 sections so as to accommodate the valve 34, as shown most clearly in Fig. 8. These arcuate plates 41 have their inner peripheries located directly between the body member 37 and the clamping plate 38, and their outer portions are 70 located between the beads 32. The parts are so proportioned that, when the holder is assembled, the plates 41 are securely clamped directly between the clamping member and the body member; one of the beads is clamped between the in- 75

termediate disc and the body member, and the other bead is clamped between the intermediate disc and the clamping member. The beads are of such size that they are compressed (when 5 the bolts 39 are tightened up) within the recesses between the members of the holder and the intermediate disc. With this arrangement, it will be seen that the cushion is securely held against movement in all directions relative to 10 the holder, this being essential to protect the valve with respect to the inner tube. The intermediate disc composed of the plates 41 through which bolts 39 pass provides an additional frictional contact between the casing and the holder. 15 The disc of the holder is formed in sections, as described, in order to facilitate assembly of the parts. These sections may be secured to the body portion by means of screws 43 before the clamping plate is brought to position. Then the 20 clamping plate is brought to position and the bolts 39 are then applied. It is observed that the cushion is positively held against movement relative to the holder and, when the cushion is inflated, the area of the engaging surfaces between 25 the outer periphery of the cushion and the car wheels is extremely liberal, and a most powerful friction clutch is obtained between the cushion and the wheel so that there is no slippage therebetween in normal operation, thus doing away 30 with wear and tear such as clutches are ordinarily subjected to when starting a dead load. With moderate pressure in the cushion, a very high driving power is obtained between the rubber of the cushion and the metal surface of the 35 wheel, acting at a point close to the tread of the wheel.

The body member 37 has a tapered opening which receives the tapered end 45 of the hollow shaft or quill so that the holder has a wedged fit 40 on that tapered portion. Inwardly of the tapered portion 45, the hollow shaft 30 has a substantial thread 46 on which is screwed a ring or nut 47 provided with a plurality of holes 48 of considerable number, for example, eight. Extending 45 through these holes are bolts 49, which also project through aligned openings in the body portion 37. The holder is fixed to the quill 30 against turning movement relative thereto by means of a key 50. With this arrangement, it will be observed 50 that the holder for the pneumatic cushion may be very securely and effectively fastened to the shaft against endwise and rotary movement relative thereto. The arrangement also is a very simple and economical one, and permits of ready 55 assembly and dis-assembly of the parts. If desired, the ring or nut 47 may have additional threaded openings for the reception of screws 51 the outer ends of which are adapted to bear against the body portion 37. The advantage of 60 this is that when it is desired to remove the holder and the cushion from the shaft, this can be easily done by turning the screws 51 in the proper direction so that the ends thereof bear against the body portion 37. 65 The bevel gear drive will now be described, particular reference being had to Fig. 6. Located upon the tubular shaft, midway between its ends, is a gear casing or housing 60 within which are located a driven gear 61 fixed to the tubular shaft 70 and a driving gear 62 fixed to the drive shaft section 14. The gears 61 and 62 are bevel gears, their axes of rotation being disposed at right angles to one another. The gear 61 is fixed to the shaft 30 by bolts 63 or by other suitable fastening means. 75 The casing is supported by frictionless bearings

which are preferably of the Timken type. One of these bearing units, designated by the numeral 64, is located in one end of the casing and has an outer ring 65 and an inner or oil retaining ring 66. The opposite end of the body portion of the casing is closed by a removable plate 67 secured in place by a plurality of screws 68. The purpose of this removable plate is to permit of the placing of the gears within the casing. The plate 67 being removed, the gear 62 may be introduced into the housing 60 through this open end and secured in proper position upon the shaft section 14; the gear 61 having been secured to the shaft 30, the housing 60 may then be threaded over the shaft 30 and gear 61 until the latter is disposed in proper position within the housing. Carried by this plate 67 is a bearing unit 69 similar in construction to the bearing unit 64. The casing is adjustable lengthwise of the shaft 30 to permit of a proper relation between the gears when final adjustment takes place, and is adapted to be secured in adjusted position by nuts or rings 70 and 71 bearing against the outer rings 65 of the bearing units. In order to secure the nuts against turning movement, each of them has a plurality of 25 angularly spaced apart slots 72, thus providing the nuts with yielding portions 73. Extending through these yielding portions and into the body of the nut are screws 74. By adjusting the rings or nuts 70 and 71, the gear 62 may be brought 30 laterally into proper meshing relation with the gear 61. To accomplish this result, one of the nuts is loosened up and then the other is screwed up, care being taken that the bearings are set right. After the casing has been properly adjusted by means of the rings 70 and 71, these rings, by tightening the screws 74, may be wedged or cramped against the threads on the shaft without disturbing the adjustment. Also, the clamp bolts may be set securely without injury to the major 40 threads, because of the presence of inserted washers 72 selected as to proper thickness, and which limit the action on the large ring nuts at each slot. 45 The casing 60 has a tubular extension 76 radially disposed with respect to the axis of the tubular shaft, and within this extension is a sleeve 77 which carries the drive shaft 14. Interposed between the sleeve 77 and the drive shaft are anti-friction bearing units 78 and 79 which may also be of the Timken type. The bearing units may be adjusted by a nut 80 which screws onto the shaft 14 and bears against the outer plate 81 of the unit 78. This nut is split and is provided with a transverse bolt 82 so that, after the nut is adjusted, it 50 may be securely clamped in place. The sleeve 77, and the shaft carried thereby, are adjustable as a unit in order to bring the gears into proper meshing relation after the gear box has been adjusted axially of the tubular shaft. For this purpose, the forward end of the sleeve is threaded so as to receive a threaded clamping nut 83 adapted to be secured to the gear casing by screws 84. By preference, the clamping ring or nut 83 is split and is drawn tightly about the threaded portion of the sleeve by a transverse bolt 85. This arrangement provides for a very nice and fine adjustment. The driving shaft bearings and the shaft are assembled in the sleeve and the bearings are nicely adjusted before the sleeve is placed in 55 the tubular extension. The sleeve is then inserted, and the driving gear is then placed and fixed on the inner end of the shaft from within the casing. The screws 84 are put in place, but not tightened up, so as to hold the clamp nut against 60 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

the casing and prevent the clamp nut from turning, while adjusting the sleeve. The sleeve may now be rotated, to adjust the gear 62 relative to the gear 61. After the adjustment is made, the 5 clamping bolt 83 and the screws 84 are turned up so as to securely lock the parts in adjusted position, and this is done without disturbing the adjustment of the bearings or the adjustment of the shaft 14 with respect to its sleeve.

10 In order to prevent rotation of the gear casing, there is provided a torque rod 86, which is most clearly shown in Figs. 4, 9, and 10. This rod has a forward tapered end 87 which fits in a similarly tapered hole 88 provided in the rear of the gear 15 casing. The rod is secured against withdrawal from this opening and against turning movement by means of a nut 89. The rear end of the bar extends over the top plate 27 and through a block 90 secured to the top plate by bolts 91, the nuts 20 of which bear on a face plate 92 placed on top of the block. This block is preferably made of hard wood, such as maple. Preferably, a number of these blocks are provided, each having an opening for the torque rod, and the openings of the 25 several blocks being of different heights. Before anchoring the rear end of the torque rod, the car is totally assembled so that the truck springs are under full weight and then that block is selected which will hold the torque rod and casing in a 30 position where the sections of the drive shaft are aligned and thus the knuckle joints 15 and 15' are favored.

From the description of the invention so far made, it will be observed that the driving unit 35 is located upon and carried by the tubular shaft which is resiliently supported by the wheels so that the transmission of shocks and jars from the wheels as they pass over the rails to the driving mechanism is, to a large extent, eliminated, which means that wear and tear on the 40 driving system is greatly reduced, and the car may be driven at very high speeds for greater distances with a greater degree of safety than has heretofore been possible. The cushions also 45 take care of lateral thrusts and jars on the car. The drive unit is shielded from dust and may be maintained in perfectly lubricated condition at all times. The parts may be readily assembled and dis-assembled, and they may be readily 50 adjusted when necessary.

Referring now to the construction of the trucks, each includes, as hereinbefore stated, a pair of H-beams 25 connected together by the I-beams 26 and the top plate 27. Located upon each of 55 the H-beams is a pair of opposed springs 100 and 101, each of which preferably consists of a single integral member which tapers down in thickness from its central portion towards its ends. The lower spring 101 is secured to the 60 H-beam by means of screws 102. These screws extend upwardly through the flanges of the H-beam and are surrounded, between those flanges, by tubes 103, as shown in Figs. 3 and

5. The H-beams, adjacent their central portions, may be reinforced by tapered plates 104. Secured, as by means of bolts 108, to the ends of the upper spring 100 are rocker plates 105. These rocker plates comprise integral members having grooves in their upper surfaces which receive the respective ends of the spring 100. Each plate has a depending curved or rounded fulcrum or edge 107. Secured to the opposite ends of the spring 101, as by means of bolts 110, are saddles 106. These saddles are grooved to receive this spring and thus prevent side play be-

tween these two parts. On the upper face of each saddle 106 is a block portion having a transverse groove 109 in its upper face. The bottom of this groove provides a surface on which a respective fulcrum 107 is adapted to rest. In order to prevent lateral movement of the springs one relative to the other, I provide, at each end of the springs and on opposite sides thereof, side plates 111 which are held tightly against the opposite side edges of the saddles by bolts 10 113 which straddle the block portion of the saddle 106. There is a clearance between these side plates and the rocker plates. As shown in Fig. 3, the rear and front faces of this block portion are grooved so as to accommodate the bolts 113. 15 The plates 111 are thus held against movement relative to the lower saddle. The lower edges of these plates 111 are bent inwardly and extend beneath the spring 101 so as to prevent the spring from separating from the rocker 20 plates. A pin 112 carried by the side plates and located above the spring 100 prevents that spring from separating from the fulcrum plates. In operation, the two springs 100 and 101, under 25 changes in pressure, are shortened up and lengthened out and, in these flexing operations, there is only a rolling motion between the rocker plates and the saddles. Friction and resultant wear are reduced to a minimum.

The underslung H-beams 25 are suspended 30 from journal boxes 24 in which the opposite ends of the axles are journaled. The four journal boxes on each truck may be of like construction and, therefore, a description of one will apply to all. In the present illustrative disclosure, each 35 journal box has a casing 115 in the opposite ends of which are located bearing units each comprising an outer race 116, an inner race 117, and roller bearing units 118 therebetween. The bottom of the casing has a groove 119 which receives the upper flange of the H-beam, that beam being somewhat narrowed where it enters the recess of the bearing casing. The front and rear sides of the casing 115 are provided with vertical grooves 120 which receive the upright 40 portions of a pair of spaced brackets 121 secured to the top of the H-beam 25. These brackets may be secured in place by means of rivets 122 and bolts 123. The latter extend through the flanges of the H-beam and are surrounded 45 by tubes 124, as is the case with the screws 102. These brackets constitute guides which are adapted to move vertically in the side grooves of the journal box as the truck moves up and down with respect to the axles. The vertical grooves 50 120 are of increased depth at their upper ends yet much narrower so as to provide upwardly facing shoulders 125 on the casing 115. Carried by the brackets 121, adjacent their upper ends, are screws 126 which extend over the shoulders 55 125 in order to prevent the truck beam from falling down in the event a spring 130 should break.

The truck beams are suspended or underslung from the journal boxes in the following 60 manner: extending longitudinally of the truck beams and supported upon the top of each journal box is a spring 130 preferably formed of a single integral member which tapers down in thickness towards its opposite ends. This spring 65 is held against endwise and lateral movements by means of a pin 131 carried by the journal box and extending into a recess in the spring. The opposite ends of the spring are curved upwardly, as at 132. Secured to the H-beam 25 below 70 75

the opposite ends of the spring 130 are brackets or hangers 133 each having a hooked portion 134. The brackets of each pair face away from each other, and the hooked portions extend transversely of the H-beam. These brackets may be secured in place by bolts 135 about which are tubular members 136 comparable to the tubes 124. Between each end of the spring 130 and the corresponding bracket 133 is a link 137 which has its upper end turned horizontally and then downwardly and its lower end turned horizontally and upwardly. The downwardly turned end 138 engages and is fulcrumed on the spring inwardly of the hooked portion 132. The upwardly turned portion 139 of the link engages the underside of the hooked portion 134 of the bracket. In order to prevent lateral movement between the link and the spring 130, the downwardly turned portion 138 may have a notch 140 which receives the stud 141 carried by the spring. Also, in order to prevent lateral movement between the lower end of the link and the bracket 133, the up-turned portion 139 of the link may have a notch 142 which receives the end of a screw 143 carried by the bracket. It will thus be observed that the underslung truck is suspended on the bearings or journal boxes which are supported by the wheeled axles, and the springs 130 supplement the main springs 100 and 101 in order to provide for easier riding qualities, and at the same time to protect the truck frame from serious vibration or shocks.

The links 137 are so associated with the springs 130 and brackets 134 as to permit unrestricted flexure of the springs without introducing any substantial amount of friction between these parts. Reference has been had to the tubular members 103, 124, and 136 which encircle the bolts for securing certain parts of the H-beams 25. These tubular members serve a very useful purpose in that they strengthen and reinforce the flanges of the beams between which they are inserted and prevent failure of those flanges. Obviously, the provision of a number of openings in the flanges for the reception of the several securing screws or bolts tends to weaken those flanges, but this weakening effect is more than compensated for by the tubular members.

The body portion or platform of the car is supported by the springs 100 and 101 through a bridge bar 150 and hardened side bearing rollers 151. The bridge bar 150 comprises a rigid, strong bar which extends transversely of the springs 100 and rests thereon. This bar has down-turned end portions 152 which terminate in horizontally disposed and outwardly extending trunnions 153 on which the side rollers 151 are journaled, as shown most clearly in Fig. 5. The bar is secured to each spring 100 by means of screws 154 and a clamp plate 155 through which the screws extend. Secured to the underside of the outer I-beams 9 of the platform of the car are short I-beams 157 to the underside of which are fastened hardened side bearing plates 158 which rest upon the rollers 151. Obviously, the purpose of the side bearing rollers is to permit of such pivotal movement between the trucks and car body as is necessary when the car passes about a curve in the track or is switched from one track to another. It will be observed that the means for supporting the car body on the springs of the truck, while being very simple in construction, is effective in operation. It comprises but a relatively few number of parts, each 75 of which is strong and durable, and these parts

may be readily assembled and, when assembled, are secure.

Reference will now be had to the central pivot about which the truck is adapted to turn in a horizontal plane, particular reference being had to Figs. 3, 4, and 5. The pivot pin 160 for the truck is located centrally of the truck and midway between the rollers 151. The pin extends vertically from, and is appropriately secured to, an anchor member 161 riveted to a plate 162 which is secured to the two central longitudinally extending I-beams 9 of the car platform. This plate may be secured to those I-beams by clamp bars 163. Mounted for sliding vertical movement on this pin is a spherical ball 164 which is received in a spherical socket provided by a casing having the parts 165 and 166. This casing is located on, and is secured to, the top plate 27 which, as previously stated, ties together the two beams of the truck. The member 165 of the casing has a depending housing 167 into which the lower end of the pivot pin is adapted to extend, as shown most clearly in Fig. 5. This housing is adapted to be filled with a suitable lubricant. The lubricant may be supplied by pouring it through a longitudinal opening 168 in the pin, and the upper end of that opening may be closed by a nut cap 169. A flexible jacket 170 between the anchor member and the casing may be provided to protect the pivot pin and ball socket against grit and dirt. It will be observed that, with this arrangement, the pivot pin 160 may move up and down relative to the ball, thus permitting of a vertical movement of the car platform with respect to the trucks. Also, owing to the universal joint provided by the ball 164 and the casing therefor, the car body may have a rocking movement with respect to the truck and, of course, the trucks may have a pivotal movement about a vertical axis. The contacting surfaces between the pivot pin and the ball, and between the ball and its casing, are maintained in a thoroughly lubricated condition as the engagement between these surfaces is continuously changing, thus avoiding wear at any localized points, and the lubricant will be forced up between these surfaces as the pin moves up and down in the oil chamber.

Each wheel 10 is secured in place on the tapered portion 29' of the shaft 29 by means of a split clamping nut 171, as most clearly shown in Fig. 7. Between the shaft and the wheel is a key or spline 172. The outer end of the hub of the wheel may be externally threaded, as at 173, so as to receive a disc (not shown) having suitable threaded openings adapted to receive draw bolts or screws by means of which the wheel may be pulled loose of the tapered portion 29' when it is desired to renew the cushions or make repairs or adjustments. Normally, the threaded portion 60 of the hub may be encircled by a protecting ring 174.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of 70 75

the scope of the invention which, as a matter of language, might be said to fall therebetween.

I claim as my invention:

1. In a drive for railway cars, a pair of removable driven wheels, an axle to which said wheels are secured, a shaft about said axle and spaced therefrom, driving means on said shaft, a holder secured to each end of said shaft and having a body portion removably secured to the shaft and a clamping ring removably secured to the body portion, a pneumatic cushion surrounding the holder and having a casing provided with beads, and an inner tube in the casing, said beads being clamped between said body of the holder and said ring, each of the driven wheels having an annular container, the interior surface of which is adapted to receive the peripheral surface of the cushion.
2. In a drive for railway cars, a pair of driven wheels each having an annular internal surface parti-elliptical in cross section, an axle to which said wheels are secured, a shaft about said axle, a holder secured to each end of said shaft, and a pneumatic cushion surrounding and secured to each holder and having a casing and an inner tube, the peripheral surfaces of said casings conforming to and being in close engagement with the parti-elliptical internal surfaces of said wheels.
3. In a drive for railway cars, a pair of wheels each provided adjacent its tread with an annular internal surface parti-elliptical in cross section, an axle to which said wheels are secured, a shaft about said axle and spaced therefrom, driving means on said shaft, a holder secured to each end of said shaft, and a pneumatic cushion surrounding each holder and having a casing and an inner tube in the casing, said casing being elliptical in cross section, the peripheries of said pneumatic cushions being adapted to tightly engage against the internal surfaces of said wheels when the cushion is inflated whereby a dependable driving engagement is had between the cushions and the wheels.
4. In a drive for railway cars, a driven wheel having an annular container provided with an interior surface, an axle to which said wheel is secured, a shaft about said axle and spaced therefrom, a holder secured to the end of said shaft and having a body portion removably secured to the shaft and a clamping ring removably secured to the body portion, said body portion and clamp having inclined flanges forming a seat, and a pneumatic cushion surrounding said holder and mounted on said seat and having a casing provided with beads and an inner tube in the casing, said holder and clamping ring being recessed at the base of said seat so as to conform to and closely receive and securely bind said beads, the periphery of said casing, when inflated, being in tight engagement with said internal surface of said container.
5. In a drive for railway cars, a driven wheel having an annular container provided with an intermediate surface, an axle to which said wheel is secured, a shaft about said axle and spaced therefrom, a holder secured to said shaft and located within said container, and a pneumatic cushion about said holder and having its periphery, when the cushion is inflated, in tight driving engagement with the internal surface of said container, said pneumatic cushion comprising a casing having beads on its inner periphery and an inner tube in the casing, said holder comprising a body portion secured to said shaft, a clamping member and an intermediate plate between said clamping member and body portion, said body portion and clamping member having oppositely directed flanges on their outer edges constituting a seat, the opposed faces of said body portion and clamping member being recessed at the base of said seat to conform to the shape of said beads and said intermediate plate being interposed between said beads.
6. In a drive for railway cars, a driven wheel having an annular container provided with an internal surface, an axle to which said wheel is secured, a shaft about said axle and spaced therefrom, a holder secured to said shaft and located within said container, and a pneumatic cushion about said holder and secured thereto and having its outer periphery in close driving engagement with the internal surface of said container, said pneumatic cushion having a casing with beads on its inner periphery and an inner tube within the casing; said holder having a body portion removably secured to said shaft, a clamping member, an intermediate plate and bolts for securing said clamping member and plate to said body portion, said body portion and clamping member having peripheral surfaces constituting a seat for said casing, the opposed faces of said clamping member and body portion, at the base of said seat, being provided with recesses conforming to and adapted to closely receive and securely bind said beads, said plate having its outer portion located between said beads and its inner portion directly interposed between said body portion and clamping member, said bolts extending through said clamping member, intermediate plate and holder for securing the parts together and compressing said beads between the clamping member and holder and against said intermediate plate.
7. In a drive for railway cars, a driven wheel having an annular container provided with an internal surface, an axle to which said wheel is secured, a shaft about said axle and spaced therefrom, a holder secured to said shaft and located within said container, and a pneumatic cushion about said holder and secured thereto and having its outer periphery in close driving engagement with the internal surface of said container, said pneumatic cushion having a casing with beads on its inner periphery and an inner tube within the casing; said holder having a body portion removably secured to said shaft, a clamping member, an intermediate plate and bolts for securing said clamping member and plate to said body portion, said body portion and clamping member having peripheral surfaces constituting a seat for said casing, the opposed faces of said clamping member and body portion, at the base of said seat, being provided with recesses conforming to and adapted to closely receive said beads, said plate having its outer portion located between said beads and its inner portion directly interposed between said body portion and clamping member, said bolts extending through said clamping member, intermediate plate and holder for securing the parts together and compressing said beads between the clamping member and holder and against said intermediate plate comprising a plurality of arcuate sections positioned end to end.
8. In a drive for railway cars, a pair of driven wheels, an axle to which said wheels are fixedly connected, a hollow shaft about and spaced from said axle, driving means on said shaft, the opposite ends of said shaft being tapered, a holder

wedgedly fitting on each tapered end of said shaft, threaded rings screwed on said shaft inwardly of said tapered portions, screws between said rings and holders, each of said holders having a body portion and a clamping ring, the outer peripheries of which constitute a seat for a pneumatic cushion, and said pneumatic cushion being mounted on said seat and being clamped between said holder and ring, each of said wheels 10 having an annular internal surface parti-elliptical in cross section, the outer periphery of said cushion being adapted to engage tightly and be flattened out against said surface.

9. In a drive for railway cars, a driven wheel 15 having an annular container provided with an intermediate surface, an axle to which said wheel is secured, a shaft about said axle and spaced therefrom, a holder secured to said shaft and located within said container, and a pneumatic

cushion about said holder and having its periphery, when the cushion is inflated, in tight driving engagement with the internal surface of said container, said pneumatic cushion comprising a casing having beads on its inner periphery, and 5 an inner tube in the casing, said inner tube having a valve stem, said holder comprising a body portion secured to said shaft, a clamping member and an intermediate plate between said clamping member and body portion, the opposed faces 10 of said body portion and clamping member being recessed to conform to the shape of said beads, and said intermediate plate being interposed between said beads, said intermediate plate comprising a plurality of arcuate sections positioned 15 end to end, the adjacent ends of two of said sections being spaced apart to accommodate said valve stem.

CHARLES DE LOS RICE.
